ROTARY PUMP

Edward W. Tilton, Oshkosh, Wis., assignor of
one-half to Harry R. Kay, Winnetka, Ill.

Application December 18, 1936, Serial No. 116,457

2 Claims. (Cl. 103—144)

My invention relates to rotary pumps and particularly to rotary pumps of the impeller or vane type, such as are used for pumping oil, water, milk, pulp, and other liquids.

5 Stated generally, the principal object of the present invention is to provide an improved rotary pump of the impeller or vane type which shall be more efficient in operation, less expensive to construct and manufacture, and easier to repair, 10 clean, and service than any of the pumps heretofore known to the art. Somewhat more specifically, it is an object of the present invention to provide an improved rotor structure for use in pumps of the subject type; to provide an improved 15 impeller assemblage for use in pumps of the subject type; and to provide an improved seal and bearing structure for use in pumps of the subject type.

These and other objects of the invention, and 20 the preferred method of accomplishing the same will be made more apparent by reference to the following description taken in conjunction with the attached drawings, wherein—

Figure 1 is a sectional view through a rotary 25 pump embodying the features of the present invention;

Figure 2 is a sectional view on the line 2—2 of Figure 1;

Figure 3 is an exploded perspective view showing the rotor, the impeller assemblages, and certain other of the structural features of the pump illustrated in Figures 1 and 2;

Figure 4 is a perspective view of one of the impeller assemblages;

35 Figure 5 is an elevational view, partially in section, of one of the impeller assemblages;

Figure 6 is a sectional view showing the features of one of the roller members which serve to connect the impeller blades to the rotor proper;

40 Figure 7 is an end elevational view of this roller support, the view being taken on the general line 7—7 of Figure 6;

Figure 8 is a sectional view on the line 8—8 of Figure 6; and

45 Figure 9 is a fragmentary, perspective view of one of the combined bearing and seal structures forming a part of the pump illustrated particularly in Figures 1 and 2.

The pump illustrated in the drawings includes 50 a generally cylindrical housing 1 preferably of cast metal. Suitable feet 3 for attaching the pump to the supporting structure therefor are cast integrally with this housing. Intake and discharge passageways 5 and 7, respectively, are 55 provided in the walls of the housing 1, the outer

portions of these passageways being defined by suitable hollow bosses or projections 9 and 11 cast integrally with the housing. The outer ends of these projections may be conveniently threaded for connection to pipes or the like, as at 12. 5 To give increased rigidity to the housing, centrally disposed external ribs 13 are cast integrally therewith, the ribs 13 extending between the feet 3 and the inlet and outlet passageway defining projections 9 and 11. 10

The bore 15 of the housing 1 is accurately machined to a cylindrical form, and the two ends of the housing 16 and 17 are machined flat in planes substantially perpendicular to the axis of the bore 15. Spaced holes 19 are provided in the 15 side walls of the housing 1 for receiving tie bolts 20 which serve to hold the stationary parts of the pump in the assembled position.

The housing 1 is closed at either end thereof by an end plate 21, preferably of cast metal. 20 Each of the end plates 21, as is particularly illustrated in Figures 2 and 3, includes an inwardly projecting, hollow boss 23, the outer surface 25 of which is accurately machined to a cylindrical form. Each of the bosses 23 is provided with an 25 inner bore 26 eccentrically disposed with respect to the outer surface 25 thereof, and with a cylindrical opening 27 for receiving the shaft 29 forming a part of the pump rotor.

A somewhat similar hollow boss 31 projects 30 outwardly from the outer surface of each of the end plates 21, the bosses 31 having a cylindrical bore 33 for receiving the bearing and the gland seal, which will be described in detail later. The outer edge of each of the end plates 21 is re- 35 cessed to form a flange 34 for engaging the end surfaces 16 and 17 of the housing 1, and suitable holes 35 are provided in the flange 34 for receiving the tie bolts 20 which extend through the holes in the housing. 40

It will be seen that when the end plates 21 are fastened in position upon the housing 1, the space enclosed thereby will be substantially cylindrical in form. The pump rotor is adapted to move within this space and includes a generally 45 cylindrical body member 37 press-fitted and keyed to the rotor shaft 29 which extends through the aligned openings 27 in the end plates 21. At either end thereof the rotor body 37 is undercut by an annular recess 39 for receiving the 50 bearing portions of the impeller assemblages 41 which are mounted upon the inwardly projecting bosses 23 forming a part of the end plates 21. The rotor body is provided along the periphery thereof with a plurality of longitudinally extend- 55

ing, regularly spaced, cylindrical slots 43 for receiving the impellers and their supports. These slots 43 are open along the periphery of the pump rotor 37 and connect with the annular recesses 39 at either end thereof. In the pump illustrated in the drawings, the rotor body 37 is provided with four of the slots 43. It will be understood that any number of such slots as is indicated by the design of the pump may be used.

10 The end surfaces 45 of the rotor body 37 are machined flat in planes substantially perpendicular to the axis of rotation of the rotor, and the longitudinal width of the rotor is made slightly less than the width of the space enclosed 15 between the end plates, i. e., sufficient clearance being provided to accomplish a good running fit between the end plates 21 and the ends of the rotor body. For pumps of moderate capacity, a clearance of two-thousandths of an inch will generally be found satisfactory for this purpose. If desired, shims may be used intermediate the end surfaces 16 and 17 of the housing and the adjacent surfaces of the end plate flanges 34 for permitting adjustment of the width of the enclosed space during the operative life of the pump.

10 The impeller assemblages 41 forming a part of the pump of my invention are illustrated particularly in Figures 3, 4, and 5, and as will be seen from inspection of those figures, each of these assemblages includes a pair of impeller members 47 and 48 which are normally assembled in cooperative unitary relationship. For convenience, I have designated one of these impeller members (the member 47) as the male member and the other (the member 48) as the female member. Both types of members are provided with an impeller blade 49 generally rectangular in cross section.

40 Each of the impeller members also includes an annularly shaped hub or bearing portion. The hub portion of each of the male members 47 is provided with a cylindrical bore 52 adapted to be journaled upon the outer surface 28 of one of the inwardly projecting bosses 23 forming a part of each of the end plates 21. The outer surface of the bearing portion of each of the male impeller members 47 is provided with an annular recess 53 which is adapted to engage a suitable flange forming a part of the hub portion of the cooperating female member 48 with a bearing fit. By virtue of this arrangement, the two impeller members may be assembled into the unitary relationship, shown particularly in Figures 4 and 5, and each of these units can then be journaled upon one of the inwardly projecting bosses 23 forming a part of each of the end plates 21, as illustrated in Figure 2. It will be seen that this arrangement permits the maximum possible bearing surface for each of the impeller assemblies, which necessarily rotate at the same speed as the pump rotor, and yet at the same time it permits relative movement about the axis of rotation of the unit as a whole between the male and female impeller members making up each of the impeller assemblages. This constructional arrangement of the impeller units is one of the important features of the present invention.

70 The impeller blades 49 are driven by the rotor, and for mechanically interconnecting the rotor with the impeller blades, I utilize slotted, cylindrical rollers 51, the features of which are illustrated in Figures 6, 7, and 8. One of the rollers 51 is positioned within each of the cy-

lindrical slots 43 in the rotor, and the engaging surfaces of the slots and the rollers are machined to a bearing fit. The impeller blade 49 forming a part of each of the impeller members is adapted to be disposed within a longitudinal rectangular slot 55 formed in each of the blade supporting rollers 51. To secure the best mechanical advantage, it is desirable that this slot 55 shall have a depth greater than one-half the diameter of the roller, and to minimize the width 10 of the pump, one end of each of the rollers 51 is provided with a transversely extending slot 56 which aligns with the annular recess 39 in the rotor body 37 to receive the right angle portion 15 of the impeller extending between the blade and the hub portion thereof.

This arrangement permits the width of the entire rotor, including the cooperating impeller assemblages, to be kept the same as the width of the impeller blades, thereby simplifying the problem of securing a good seal within the pump, and also materially aiding in reducing the space occupied by the pump.

I prefer to utilize roller bearings in conjunction with the pump of my invention, but it is 25 to be understood that other types of bearings may be successfully employed. It is, of course, desirable that the bearings shall accurately position the rotor within the housing and shall be of a low friction type. The bearing and seal assemblage illustrated particularly in Figures 2 and 30 45 is intended for use with a roller bearing. As will be seen by reference to those figures, the bore 33 formed in each of the end plates 21 is partially closed at its inner end by an annular 35 member 57 which defines a suitable retaining surface for a gasket, and a gasket 58 of the conventional trapezoidal cross section type is placed against the outer surface of this member during the assembling of the pump so as to surround 40 the rotor shaft 29.

An annular gasket retaining ring 59 of suitable dimensions is next introduced into each of the bores 33. This ring is followed by a roller bearing assemblage 60 of the conventional type, 45 the outer race of which is adapted to abut against the gasket retaining ring. Preferably, the gasket retaining ring is recessed, as at 61, to positively prevent any interference with the movable race of the bearing. The next element 50 in the bearing and seal assemblage is a combined bearing and lubrication retainer 62. This member, as is shown particularly in Figure 9, is generally cylindrical in its outer dimensions and is provided with an annular recess 63 machined in 55 the inner surface thereof for providing a lubrication well. Lubricant is admitted into this recess through a suitable opening 64 formed in the upper portion thereof, and the proper positioning of the retainer member 62 is assured during the 60 assembling operation by means of a pin 65 which is adapted to engage a suitable slot formed in the wall of the adjacent outwardly projecting boss 31.

After the gasket 58, the gasket retaining ring 65 59, the bearing 60, and the bearing and lubricant retainer 62, have been placed in position within each of the bores 33, a suitable retaining nut 67 is screwed in position so as to hold the several elements in place and to tighten the gland seal. 70 It will be seen that the number of structural features utilized in making up each of the bearing and seal assemblages is reduced to the barest minimum, and that substantially all of the elements are called upon to perform more than one func- 75

tion, the outer race portion of the bearing 60, for example, serving to transmit the stress induced by the retaining nut 67 to the gasket retaining ring 59, and the bearing retainer 62 5 also serving as a lubricant retainer. The entire assemblage is a simple and highly efficient arrangement, and not only serves to give a good seal between the shaft and the interior of the pump, but in addition constitutes a seal which is 10 particularly free from any possibility of contamination, this feature being of great importance when the pump is used for handling milk or like liquids. Further, this arrangement permits the pump to be easily disassembled, as for cleaning.

15 During operation of the pump, power is applied to the rotor shaft 29 from any suitable source. Due to the eccentricity of the axes of rotation of the impeller assemblages and the rotor, the impeller blades 49 project from the 20 surface of the rotor at all times except when they are passing across the seal point 69 at the upper portion of the pump housing. The amount of this projection varies from zero or less at this upper or seal point to a maximum at the bottom 25 of the pump casing. The bore 15 of the housing 1 is concentric with the axis of rotation of the impeller assemblages 41, and hence a very close fit may be maintained between the impeller blades 49 and the inner surface of the bore at all 30 times during operation of the pump. This makes for high heads and high pumping efficiency. At the same time, the retractable feature of the blades assures a complete cutting off of the inlet and outlet sides of the pump at the seal point 69.

35 It is apparent that there is substantial relative movement between the impeller blades 49 and the supporting rollers 51 therefor during operation of the pump. Because of this, it is desirable that the spaces beneath the impeller blades 40 shall be connected in order to minimize any possibility of excessive friction due to unequal pressure distribution. In the pump illustrated in the drawings, this interconnection is accomplished by four passageways 71 (Figure 1). The outer 45 portion of each of the passageways 71 is preferably formed by a suitable drilling in one of the roller members 51, and the inner portion of each of the passageways 71 constitutes a connecting drilling which extends through the rotor body 37 and the shaft 29. The drillings through the 50 shaft preferably intersect and connect with each other so as to attain the best possible equalization of pressure during the operation of the pump.

It will be also apparent that there is a certain 55 amount of relative angular movement between the impeller blades 49 and the rotor body 37 during the operation of the pump. It is for this reason that the roller members 51 engage the slots 43 within the rotor body with a bearing fit, and that the 60 impeller blades 49 engage the slots 55 within the rollers with a bearing fit.

In connection with the operation of the pump of my invention, I have found that the positioning and form of the inlet and outlet ports 5 and 7 65 is of considerable importance. Particularly, I have discovered that if the ports are extended along the bore of the housing 1 so that the actual working surface of the bore of the pump subtends an angle no greater than the angle between two adjacent impeller blades, substantial 70 improvement of performance will result. This is accomplished in the pump illustrated in the drawings by the provision of a rectangularly shaped slot 72 formed in the side walls of the 75 housing, which slot is extended down to a point

within 45° of the horizontal, as indicated at 73. The width of the slots 72, as is shown in Figure 2, is purposely made substantially less than the width of the impeller blades 49 in order to accomplish the most efficient and quiet operation 5 of the pump. Through the arrangement of these slots 72, the actual pumping or working portion of the pump is confined to the space enclosed by two of the impeller blades. Actual tests have shown that this assures much more satisfactory 10 and more reliable operation than has ever been accomplished in any of the prior art devices. It also permits the pump to be used for pumping liquids which contain rather large amounts of solid material, such as grit, metallic oxides or 15 scale, machinings, and the like. The pump is completely reversible, as will be apparent from inspection of the drawings.

From the foregoing, it will be seen that I have disclosed the features of an improved form of 20 impeller pump which operates much more efficiently and much more satisfactorily than any of the pumps heretofore developed. This improved operation is brought about, to a considerable extent, by virtue of the novel arrangement 25 of the impeller assemblages, which assures a large bearing surface for each of the impeller assemblages as a whole while at the same time preventing any undue increase in the dimensions of 30 the pump.

The pump of my invention is an exceedingly compact structure, and there is substantially no waste space whatsoever within the pump housing. This means that no liquid is retained within the pump for any material interval of time, 35 which is of great advantage from a sanitary viewpoint when pumping perishable liquids such as milk, and of great advantage from the viewpoint of preventing clogging when pumping liquids containing solid material. The novel structural arrangement of my pump permits ready disassembly thereof, thus particularly adapting it for use in pumping milk or other food products and for the pumping of pulp solutions which have a notorious tendency to clog pumps of all 40 types. The improved pump of my invention secures a much more positive and more accurate control over the movement of the impeller blades 45 than was heretofore believed possible of attainment, and this control is accomplished with a minimum of frictional effort. I have disclosed a 50 novel arrangement for the ports of the pump of the subject type, which arrangement contributes materially to the improved operation of the pump of my invention, and I have also disclosed an improved form of bearing and seal assembly which is particularly adapted for use in conjunction with the pump of my invention. Moreover, the pump of my invention is completely reversible.

It will be understood that various modifications and variations may be made in the form of apparatus embodying the principles of the present invention, and it is my intention that the claims shall be accorded the broadest reasonable construction consistent with the state of 55 the art.

I claim the following as my invention:

1. A rotary pump comprising a shaft, a body member supported on said shaft and having at each end thereof an annular recess arranged concentrically to the axis of the shaft, the outer portion of said member being provided with a plurality of cylindrical slots, said slots being open along the peripheral surface of said member, a 70

cylindrical roller member disposed in each slot, each roller being provided with a longitudinal slot, a casing for said body member, a plate for closing each end of the casing, each plate being provided with an inwardly projecting boss positioned coaxially with respect to the axis of the casing, each boss having a circular opening therein positioned eccentric with respect to the axis of the casing, an impeller assemblage comprising a pair of impeller members respectively supported upon each boss for rotation about said axis, each pair comprising a male impeller member and a female impeller member, each impeller member comprising an impeller blade connected to an annular hub, the annular hub of each male member having a cylindrical bore adapted to engage over a respective boss with a journal fit, the hub of each female member fitting over the hub of a respective male member, 20 said shaft being supported within the circular openings formed in said bosses, a pair of impeller members being positioned within each annular recess, each impeller blade being positioned within a respective longitudinal slot formed in 25 a roller member and extending through a registering peripheral opening in an associated cylindrical slot.

2. A rotary pump comprising a shaft, a body member supported on said shaft and having at each end thereof an annular recess arranged concentrically to the axis of the shaft, the outer portion of said member being provided with a plurality of cylindrical slots, said slots being open along the peripheral surface of said member and having lateral openings communicating at each end of the slot respectively with an annular re-

cess, a cylindrical roller member disposed in each slot and having at one end thereof a transverse slot registering with a respective lateral opening, each roller being provided with a longitudinal slot intersecting said transverse slot, the length of each roller being substantially equal to the length of said body member, a casing for said body member, a plate for closing each end of the casing, each plate being provided with an inwardly projecting boss positioned coaxially with respect to the axis of the casing, each boss having a circular opening therein positioned eccentric with respect to the axis of the casing, an impeller assemblage comprising a pair of impeller members respectively supported upon each 15 boss for rotation about said axis, each pair comprising a male impeller member and a female impeller member, each impeller member comprising an impeller blade connected to an annular hub, the annular hub of each male member having a cylindrical bore adapted to engage over a respective boss with a journal fit, the hub of each female member fitting over the hub of a respective male member, said shaft being supported within the circular openings formed in said 20 bosses, a pair of impeller members being positioned within each annular recess, each impeller blade being positioned within a respective longitudinal slot formed in a roller member and extending through a registering peripheral opening in an associated cylindrical slot, each blade being connected to its associated hub by a radial portion which is positioned within a respective transverse slot formed in the roller member which engages said blade. 25

EDWARD W. TILTON.
